MAURICE FITZGIBBONS, OF NEW YORK, N. Y., ASSIGNOR TO HIMSELF AND RALPH S. JENNINGS, OF SAME PLACE.

Letters Patent No. 85,919, dated January 19, 1869.

IMPROVED TRUNK.

The Schedule referred to in these Letters Patent and making part of the same.

To all whom it may concern:

Be it known that I, MAURICE FITZGIBBONS, of New York, in the county of New York, and State of New York, have invented a new and valuable Improvement in Travelling-Trunks; and I do hereby declare that the following is a full, clear, and exact description of the construction and operation of the same, reference being had to the annexed drawings, making a part of this specification, and to the letters and figures of reference marked thereon.

Figure 1, of the drawings, is a view of the top of my trunk, with the lid removed;

Figure 2 is a longitudinal section; and

Figure 3 is a vertical section thereof.

My invention relates to travelling-trunks and boxes intended for holding and protecting furs and wearing-apparel against the inroads of moths, and other like destructive insects; and

It consists in lining the interior of such trunk or box with a veneering of camphor-wood or Spanish cedar, cut with the grain of the timber in the same manner as the veneering is prepared that is used as a substitute for wall-paper; and also in providing novel and effective means for rendering such trunk or box air-tight.

The letter A, of the drawings, represents the bottom of my trunk, and the letter B is the lid thereof.

The red lines, marked a, show the camphor-wood or Spanish-cedar lining pasted on to the wood both of the bottom and lid of the trunk.

I cut a groove in the top of the trunk-bottom, ex-

tending around the same, about one-fourth of an inch in depth, and of sufficient width to receive and hold the India-rubber band next mentioned.

The letter c is a continuous band of India rubber, fitted in the groove above mentioned, and extending entirely around the box, as shown.

On the lower side of the lid, and extending around the same, I affix a flange, marked s on the drawings, which, when the lid is pressed downward, enters into the rubber band c, and, operating therewith, renders the trunk air-tight.

This arrangement not only secures the trunk against moths, (to which the odor of camphor-wood or Spanish cedar is very offensive,) but it enables the traveller to secure his clothing from sinking in water in case of a marine accident.

The odor of the camphor or cedar-wood is also very agreeable to the sense of smell in man, and that sense is gratified by the apparel stored in my trunk.

What I claim as my invention, and desire to secure by Letters Patent, is—

A trunk, having lining a, India-rubber band c, and flange s, constructed and arranged substantially as and for the purposes herein specified.

In testimony that I claim the above, I have hereunto subscribed my name, in the presence of two witnesses.

MAURICE FITZGIBBONS.
